BOTTLE COOLER

Willard L. Morrison, Lake Forest, Ill.

Application December 23, 1939, Serial No. 310,812

1 Claim. (Cl. 62—89)

This invention relates to bottle coolers and has for its object to provide a new and improved device of this description for use in cooling bottles containing beverages.

The invention has as a further object to provide a bottle cooler which shall be cheap in construction and efficient in operation. The invention has as a further object to provide a bottle cooler wherein bottles with beverage therein may be efficiently kept in a cooled condition without the bottles being immersed in water or other liquid.

In the bottle coolers as now used, the bottles are either placed in water or a fan or mechanical air moving device of some kind is used to circulate the air in the cooler. One of the objects of the present invention is to provide a dry bottle cooler which works effectively without any mechanical air moving device, such as a fan. The invention has as a further object to provide a bottle cooler which may be used either dry or with water in which the bottles are placed. The invention has further objects which are more particularly pointed out in the accompanying description.

Referring now to the drawings,

Fig. 1 is a side elevation of one form of bottle cooler embodying the invention, with parts broken away;

Fig. 2 is a sectional view taken on line 2—2 of Fig. 1;

Fig. 3 is a plan view of Fig. 1 with the cover removed; and

Fig. 4 is a diagrammatic view showing the connections and electric circuits.

Like numerals refer to like parts throughout the several figures.

Referring now to the drawings, I have shown one form of bottle cooling device embodying the invention. In this construction there is a heat insulated receptacle, which consists of a bottom 40 and upstanding sides and ends, in which the bottles are received. The interior of the bottle cooler is preferably made of a metal receptacle 1. The exterior surface is preferably made from a metal receptacle 2 and the space between the two 45 metal receptacles is filled with heat insulating material 3.

Within the receptacle 1 there are preferably provided two refrigerating members or evaporators 4 and 5 of any desired construction, but preferably of a thin plate construction, suspended in substantially parallel vertical planes, that is evaporators which are comparatively thin and made up of separated metal walls with means for circulating a refrigerant back and forth between 55

the walls. These evaporators preferably have smooth exteriors and may have pipes in them, or they may be made of the type as set out in my application Serial No. 285,130, filed July 18, 1939, 5 where the refrigerant when circulated back and forth between the walls of the plates, makes direct contact with the walls of the plates so that these walls form primary cooling surfaces.

These evaporators are suspended by any supporting means, so that there is a free space 6 between the evaporator 5 and its associated wall and a free space 7 between the evaporator 4 and its associated wall. The bottoms of these evaporators are above the bottom of the receptacle 1 so as to provide spaces 8 and 9 between the bottoms of the evaporators and the bottom of the cooler upon which the bottles to be cooled rest. As herein shown the evaporators are supported by means of the brackets 4a and 5a which are connected to the evaporators and to the wall of the cooler.

Between the evaporators is an open topped space 10 in which the bottles 11 to be cooled are located. The bottles are preferably stood up on their bottoms between the evaporators so as to be in a substantially vertical position substantially parallel to the evaporators.

The cooler is provided with a top of any suitable kind. I prefer to form the top of two doors 30 12 and 13 pivoted or hinged at 14 so that either can be moved alone. I also prefer to provide some means for preventing the doors from completely closing. This is particularly desirable when warm bottles are placed in the cooler. This result may be secured in any desired manner, as by providing stops 15 and 16 against which the doors rest, as shown in Fig. 1, thus providing cracks 17 and 18, through which the warm air escapes as the bottles are being cooled.

The evaporators may be connected to any source of refrigerant supply. I prefer, however, to provide a refrigerating apparatus arranged to form a part of the device and which is located in a receiving space 19 underneath the bottom of the receptacle 1, at one end of the device. This space preferably runs all the way across the cooler and is provided with the closing members 20 having louvers or air openings 21 therein so that air may freely circulate through the space to cool the refrigerating apparatus. This refrigerating apparatus may be of any desired form and I have shown the ordinary construction where there is a compressor 22 operated by a motor 23 and a condenser 24, the compressor and condenser being connected with the evaporators by

the pipes 25 and 26, with an expansion valve 27, in any of the usual ways.

When the device is in operation and the refrigerant circulating through the evaporators, the air on both sides of the evaporators is cooled and drops down. It will be noted that by this construction both sides of both evaporators are used to secure the cooling effect. For example, the air in the space 6 between the evaporator 5 and its associated wall is cooled and drops down and then passes under the evaporator through space 9 to the central space 10 containing the bottles. In the same way the air in the space 7 between the evaporator 4 and its associated wall is cooled and drops down and passes under the evaporator through space 8 into the central space 10 where the bottles are received. The air next to the opposed faces of the evaporators is also cooled and drops down into the space 10 where the bottles are received, so that both sides of each evaporator are used for cooling the central space 10 containing the bottles.

Some means is provided for automatically shutting down the motor when the temperature in the cooler reaches a predetermined point. As herein shown, there is provided a bulb 28 located between the two plates or evaporators 4 and 5. This bulb is connected to the chamber 29 provided with a diaphragm 30 having an electrical contact 31 therewith, to which is connected a conductor 32 which connects with the motor 23. There is an electrical contact 33 opposite the diaphragm, which is connected by a conductor 34 with one of the conductors 35 of the source of electric supply. The other conductor 36 of the source of electric supply is connected by conductor 37 with the motor. When the temperature rises above a predetermined point, the diaphragm is moved to connect the contacts 31 and 33 so as to connect the motor 23 in circuit and cause it to operate the refrigerating apparatus. When the temperature falls below a predetermined point, the diaphragm 30 is moved so that contacts 31 and 33 are disconnected and the circuit through the motor broken and the motor stopped. The size of the evaporators with relation to the size of the container and the load of bottles in the container is such that the evaporators are defrosted, yet the desired temperature is maintained throughout the cycle, this desired temperature being the temperature the user wants, a preferable temperature being a temperature of about 38 degrees Fahrenheit.

The usual type of bulb 38 to control the expansion valve 27 is provided. As shown, it is secured to the return pipe to the compressor near the evaporator 5. Any accumulation of water resulting from defrosting may be drained by removing the plug 39 from the aperture 40 in the bottom of the receptacle 1. Guard strips 41 are placed at each end of the receptacle, near the top, to protect the pipes and bulb from injury when bottles are being loaded or unloaded.

In using the device, the bottles are placed in the space 10 between the evaporators 4 and 5 and the refrigerant circulated through the evaporators so as to cool them, the cool air from both sides of both evaporators dropping down and being discharged into the space 10 between the evaporators, cold air thus surrounding the bottles and cooling them, the warm air passing up to the top of the bottle cooler. By means of this device the bottles can be quickly and effectively air cooled to any desired temperature without the use of water and without the use of any mechanical air moving device, as the evaporators by their location insure a proper circulation of the cold air around the bottles by thermosyphonic action, so as to provide a substantially uniformly cooled bottle receiving space between the evaporators.

I claim:

A bottle cooler comprising a heat insulated receptacle having a top and two separated evaporators having continuous imperforate side walls suspended in substantially vertical planes with a bottle receiving space between them open at the top, said evaporators spaced apart from the side walls and the bottom of the receptacle, so as to provide an air space between each of the evaporators and its associated side wall closed at the sides and open at the top and bottom and between the bottoms of the evaporators and the bottom of the receptacle, the air between the evaporators and their associated side walls being cooled and brought into the bottle receiving space by thermosyphonic action, the bottles being inserted and removed through the open top of the bottle receiving space between the evaporators, a door for said open top and means for holding said door partially open so that warm air may escape while it is being cooled.

WILLARD L. MORRISON.
